Primary Examiner — Dana K Weiland*Assistant Examiner* — Emily Anna Saunders(74) *Attorney, Agent, or Firm* — Tommy S F Wang; Wang IP Law Group, P.C.(57) **CLAIM**

The ornamental design for a sound generator, as shown and described.

DESCRIPTION

FIG. 1 is a perspective view of a sound generator showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exploded view thereof; and,

FIG. 9 is another exploded view thereof.

The broken lines in FIGS. 1-9 are for the purpose of illustrating portions of the sound generator that form no part of the claimed design.

1 Claim, 6 Drawing Sheets(56)
